UNITED STATES PATENT OFFICE.

JOHN R. FRENCH, OF LOS ANGELES, CALIFORNIA.

PUNCHING AND RIVETING MACHINE.

No. 918,842.

Specification of Letters Patent.

Patented April 20, 1909.

Application filed June 24, 1908. Serial No. 440,083.

To all whom it may concern:

Be it known that I, JOHN R. FRENCH, a citizen of the United States, residing at Los Angeles, in the county of Los Angeles and 5 State of California, have invented new and useful Improvements in Punching and Riveting Machines, of which the following is a specification.

This invention relates to punching and 10 riveting machines of a general type shown in a previous patent of mine No. 877,419, January 21, 1908, and shown in a prior application of mine executed June 9th, 1908. This type of machine is designed for punching and 15 riveting pipe, the operation requiring several different tools, any one of which may readily be placed in operative position.

In the two former inventions of mine, above referred to, the tools were mounted on 20 a carrier and were arranged out of line with each other as the carrier had a fixed plane of shifting movement and it is necessary that certain tools act in different planes.

The main object of the present invention is 25 to produce the necessary coaction between the tools without necessarily requiring the tools to be arranged on the carrier in line with each other. More specifically, to enable the tools to be arranged on the carrier in 30 line with each other, or substantially so, and to provide means for producing the necessary coaction between the tool on the carrier and its male or female tool on the stake by providing a relative shift of position between 35 the two sets of tools. This may be accomplished in various ways, several forms being herein shown.

Referring to the drawings:—Figure 1 is a side elevation of one form of machine. Fig. 40 2 is a front elevation of the form shown in Fig. 1 with the background of the machine omitted. Fig. 3 is a section on line x^3-x^3 Fig. 2. Fig. 4 is a view similar to Fig. 3, showing a form in which the tools are 45 mounted on a compound carrier, the stake dies being fixed in the stake. Fig. 5 is an end elevation of what is shown in Fig. 4. Fig. 6 is a side elevation of a machine equipped with a turret tool carrier and having 50 the stake dies slidably arranged in the stake, part of the stake being shown in section. Fig. 7 is a section on line x^7-x^7 Fig. 6. Fig. 8 is a side elevation showing merely the

end portions of the overhanging arm and stake, the former being equipped with a sliding tool carrier, and the latter having slideable stake dies. Fig. 9 is a side elevation of the front end of the overhanging arm and the stake, illustrating how the sliding tool carrier can be employed in lieu of the turret head of 55 Fig. 1 in connection with the sliding stake. Fig. 10 is a front elevation of what is shown in Fig. 9, part of the tool carrier being in section.

Referring to the form shown in Figs. 1, 2 and 60 3, 1 designates the frame of the machine having an overhanging arm 2 underneath which is arranged a stake 3, the latter being longitudinally slideable in the frame 1 by means of a pinion 4 which meshes with a rack 5 formed 65 on the stake 3. Pinion 4 is mounted on a shaft 6 which may be operated by a handle 7. In order to secure a close fit of the stake within the frame, after it has been adjusted to the proper position, a portion of the stake 70 75 is constructed with a wedge 8 which may be operated by rack and pinion similar to that previously described. Mounted to slide vertically in the end of the arm 2 is a head 9 operated by a crank 10 and box 11, the crank 10 80 being formed on the shaft 12 which extends through the arm 2. The head 9 has a pin 9' on which is journaled a turret tool carrier 13, the latter being operated and locked in various angular positions by means of a locking lever 14 which is adapted to engage in notches 15 formed in the head 9, as shown in Fig. 2. Secured to the tool carrier 13 is a lap laying tool 16, a punch 17 and a riveting tool 18, all of which tools are arranged in line with 85 90 each other so that as the tool carrier 13 is rotated all of said tools rotate in the same plane. Fixed near the outer end of stake 3 are stake dies comprising a female die 19, which is adapted to coact with the punch 17, 95 and an anvil 20, which is adapted to coact either with the riveting tool 18 or with the lap laying tool 16. When the punch is to be used, it is brought into central position, as indicated in Fig. 2, and the stake 3 is so adjusted that the die 19 lies directly under the punch 17. If the riveting tool 18 is to be used, the tool carrier is turned to bring the riveting tool 18 into central position, and the stake 3 is adjusted longitudinally to bring the 100 anvil 20 under the riveting tool, the stake be-

105

ing readily shifted by first operating handle 7' to loosen wedge 8, whereupon handle 7 may be operated to shift the stake, which, having been brought into proper position, is locked and firmly held in frame 1 by operating handle 7' to close the wedge 8. If the lap laying tool is to be used, the tool carrier is turned to bring the lap laying tool 16 into central position.

10 If desired, the previous form can be slightly modified by substituting the sliding tool carrier shown in Figs. 9 and 10 in place of the rotating tool carrier 13 of Figs. 1, 2 and 3. The sliding tool carrier of Figs. 9 and 10 comprises a sliding tool carrier 20' which is slideable transversely in the lower end of the sliding head 21, the latter having an enlargement 22 formed at its lower end, but otherwise having the same general construction as previously described. The tool carrier 20' is provided with three tools 16, 17 and 18, all of which are arranged in line with each other so that when the tool carrier 20' is shifted the three tools move in a single plane. The tool carrier 20' may be operated and locked in either of its three positions by means of a shaft 23 having a dog 24 which is adapted to engage with either of three notches 25 formed in the head 21. The shaft 23 is operated by a handle 26, a spring 27 serving to normally hold the offset dog 24 in engagement with a notch. By turning handle 26 the offset dog 24 may be disengaged from a notch to permit the tool carrier to be shifted. As shown in Figs. 9 and 10 the tool carrier 20' is adjusted with the punch 17 in operative position, and the sliding stake 3 is in a corresponding position. By shifting the tool carrier 20' to bring either of the tools 16 or 18 into operative position, the sliding stake 3 will be correspondingly shifted as in the previously described form.

In the forms shown in Figs. 6 to 8, the relative shift between the stake dies and tools on the head is accomplished by shifting the tools in the stake. In Fig. 6 the revolving tool carrier 13' employed is the same as used in Figs. 1 to 3. 30 designates the stake which is fixed in the frame 1, and near its outer end the stake has a dovetailed groove 31 in which is slideably mounted a block 32 as shown in Fig. 7. A groove 33 having vertical walls adjoins the dovetailed groove 31 which permits the block 32 to be inserted or removed from its sliding seat in the stake. The block 32 is provided with a female die 34 for coacting with the punch 17, while the rear portion of the block 32 is formed with an anvil 35 which coacts with the riveting tool 18 or lap laying tool 16. The block 32 is shifted by means of an operating rod 36 which is connected to it and extends through the stake 30. The rod 36 may be actuated in

any suitable manner, as, for example, by the slotted rock lever 37, link 38 and hand lever 39 which is movable over a notched sector 40. Thus by operating hand lever 39 either the anvil 35 or the die 34 may be shifted into operative position underneath the tool carrier 13'. 70

Fig. 8 shows a slight modification over Fig. 6 in that the sliding tool carrier 20' is substituted for the revolving tool carrier 13'. The sliding tool carrier 20' is similar to that shown and described in connection with Figs. 9 and 10. 75

In the form shown in Figs. 4 and 5, the tools are carried in what may be termed a compound head which comprises a lower sliding tool carrier 45 which is slidably mounted in an intermediate carrier 46, the latter being slidably mounted in an enlargement 47 on the lower end of the sliding head 9'. The intermediate carrier 46 is mounted to slide in a direction longitudinally of the stake 48, and the lower tool carrier 45 is mounted to slide at right angles to the movement of the intermediate carrier 46. The tool carrier 45 is operated and locked in its various positions, with respect to the carrier 46, by latch mechanism 26^a similar to that shown in Fig. 10, while the carrier 46 is operated and locked in its two positions on the head 9' by latch mechanism 26^b, both latch mechanisms being the same with the exception that only two locking notches are employed with latch mechanism 26^b as the carrier 46 requires but two positions, one of which holds the line of tools over the female die 19 and the other locks it in position over the anvil 20. 90 95 100

What I claim is:—

1. In a punching and riveting machine, a stake, a tool carrier, means for operating the tool carrier toward and from the stake, tools on the tool carrier, means for shifting the tool carrier in a line transverse to the stake, tools on the stake, and means for producing a relative movement between the two sets of tools in a line parallel with the axis of the stake. 105 110

2. In a punching and riveting machine, a stake, a tool carrier, means for operating the tool carrier toward and from the stake, tools on the tool carrier, means for shifting the tool carrier in a line transverse to the stake, said tools being all attached to the tool carrier in substantially the same plane, tools on the stake, and means for producing a relative movement between the two sets of tools in a line at right angles to the first mentioned line. 115 120

3. In a punching and riveting machine, a stake, a tool carrier, tools on the tool carrier, means for producing relative operative coaction between the tools and stake, tools on the stake, and means for shifting said tool carrier 125

in two different lines of direction which intersect each other.

4. In a punching and riveting machine, a stake, a tool carrier, means for producing relative operative co-action between the tools and stake, tools on the tool carrier, means for shifting the tool carrier in a line transverse to the stake, tools on the stake, and means for producing a relative move-

ment between the two sets of tools in a line 10 parallel with the axis of the stake.

In testimony whereof, I have hereunto set my hand at Los Angeles, California, this 17th day of June 1908.

JOHN R. FRENCH.
